US00D647919S

(12) **United States Design Patent**
Akana et al.

(10) **Patent No.:** US D647,919 S
(45) **Date of Patent:** ** Nov. 1, 2011

(54) **ELECTRONIC DEVICE WITH GRAPHICAL USER INTERFACE**

(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Anton Davydov**, Gilroy, CA (US); **Daniele De Iuliis**, San Francisco, CA (US); **Jorge Fino**, San Jose, CA (US); **Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Policarpo Wood**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/368,991**

(22) Filed: **Aug. 31, 2010**

Related U.S. Application Data

(63) Continuation of application No. 29/367,996, filed on Aug. 16, 2010, now Pat. No. Des. 638,030.

(57) **CLAIM**

The ornamental design for an electronic device with graphical user interface, as shown and described.

DESCRIPTION

FIG. 1 is a front bottom perspective view of an electronic device with graphical user interface showing our new design; FIG. 2 is a rear bottom perspective view thereof; FIG. 3 is a rear top perspective view thereof; FIG. 4 is a front top perspective view thereof; FIG. 5 is a front view thereof; FIG. 6 is a rear view thereof; FIG. 7 is a bottom view thereof; FIG. 8 is a top view thereof; FIG. 9 is a side view thereof; and, FIG. 10 is another side view thereof. The broken lines showing portions of the electronic device, portions of the graphical user interface, or other features thereof form no part of the claimed design.

1 Claim, 8 Drawing Sheets
